(57) **CLAIM**

The ornamental design for a glove, as shown and described.

DESCRIPTION

FIG. 1 is a top view of a glove, shown in a flattened configuration;

FIG. 2 is a right side view thereof;

FIG. 3 is a bottom view thereof;

FIG. 4 is a left side view of the glove, shown in the configuration of a relaxed hand, with the thumb abducted;

FIG. 5 is a perspective view thereof;

FIG. 6 is a front view of the glove, shown in a flattened configuration; and,

FIG. 7 is a rear view thereof.

The broken lines depict portions of the article and form no part of the claimed design.

1 Claim, 6 Drawing Sheets
